UNITED STATES PATENT OFFICE.

JAMES F. O'BRIEN, OF CHICAGO, ILLINOIS.

COMBINED POWDER MIXER AND GRANULATOR.

1,071,257.

Specification of Letters Patent. Patented Aug. 26, 1913.

Application filed January 11, 1912. Serial No. 670,646.

To all whom it may concern:

Be it known that I, JAMES F. O'BRIEN, a citizen of the United States, residing in the city of Chicago, county of Cook, State 5 of Illinois, have invented new and useful Improvements in Combined Powder Mixers and Granulators, of which the following is a specification.

This invention relates to a novel mechanism wherein different materials may be 10 mixed and granulated in a continuous operation; and the prime objects of the invention are the provision of such a machine as will carry on these operations successfully, 15 and a machine in which all possible sources of friction are entirely eliminated.

In the preferred form illustrated in the accompanying drawings, I have developed a machine particularly adapted for mixing 20 and granulating an explosive containing certain solids and certain liquid ingredients; and, although the design illustrated is particularly adapted to the class of powder which will be hereinafter described, it will be seen 25 from the following that I am not necessarily limited to this specific form of device.

Considered broadly, my invention consists first in certain mechanical arrangements whereby the operations of mixing 30 and granulating may be carried on continuously, that is, the granulation takes place in the same receptacle and immediately following the mixing; and it consists also in certain arrangements where- 35 by all possibility of friction is entirely eliminated from the machine. The preferred mechanism embodying these features consists of a rotatable barrel mounted on hollow trunnions with its axis horizontal, 40 a portion of the peripheral wall of the barrel being perforated or formed of wire screen or the like; and an oscillating member mounted on a shaft passing through the hollow trunnions and the barrel, the shaft be- 45 ing mounted in bearings which holds it entirely out of contact with the trunnions or any part of the barrel. The mixing mem- 50 bers mounted on this shaft are so formed as to become also cutting members to granulate the moist mixture to such a size to pass through the screen portion of the barrel periphery.

I will further explain the details of construction and operation in the following 55 specification, referring to the preferred

form of device shown in the accompanying drawings, in which—

Figure 1 is a side elevation of my im- 60 proved device. Fig. 2 is a sectional plan taken as indicated by line 2—2 of Fig. 1. Fig. 3 is a vertical section of the barrel in its position reversed from the position shown in Fig. 1. Figs. 4 and 5 are details showing the construction of the mixing and the cutting members.

In the drawings 5 designates a suitable 65 supporting frame which may be of any character, depending upon the housing or structure in which the machine is located. Mounted on the frame 5 is a pair of bear- 70 ings 6 which revolvably carry hollow trun- nions 7 mounted on the ends 8 of the rota- 75 ble barrel 9. Barrel 9 has a portion 10 of its peripheral wall formed of some solid material, say wooden lagging, the remain- ing portion of the peripheral wall being oc- 80 cupied preferably by a screen or wire mesh 11 and a charge opening 12. Arrangements are made, as shown in Figs. 1 and 3 so that the portion of the barrel carrying the screen 85 11 may be detached from the remaining por- tion of the barrel to render easy access to its interior. A guard 13 is provided on one side of the charge opening 12 to prevent the escape of material through the charge open- 90 ing when the machine is in operation.

Mounted in suitable bearings 20 is a shaft 21 which passes through the hollow trun- 95 nions 7 and through the barrel without en- gaging either the trunnions or the barrel. There is a suitable space left between the 90 bearings 20 and the bearing 6 so that any explosive which should happen to work out through trunnions 7 would not come into forcible engagement with the bearings 20 or be caught between the two sets of bear- 100 ings. Mounted on the shaft 21 is a suitable frame 22 projecting radially from the shaft and carrying on its outer end the mixers and cutters 23. These devices are preferably 105 formed of wire, preferably copper, in the configuration shown in Figs. 3, 4 and 5, Fig. 4 being an enlarged view of a portion of Fig. 3 while Fig. 5 is a front elevation of the portion shown in Fig. 4. From these figures it will be seen that there are certain radially projecting wires 25 and certain wires 26 placed diagonally so as to present an angular position relative to the inner pe- 110 riphery of the barrel. These portions 26

are so arranged that they will cut on their up stroke, the frame members 22 being oscillated through an angle of about 120 degrees. For the oscillation of the mixing and cutting members it is only necessary that a suitable means be provided for oscillating the shaft 21. This is typically formed by a crank device including a crank 30 mounted on a shaft 31, a connecting rod 34 connecting the crank 30 with an arm 32 on the shaft 21, and suitable means, such as pulleys 33 for rotating the shaft 31.

In operation the device is first placed in the position shown in Fig. 1 and the solid ingredients of the powder introduced through charge opening 12. The shaft 31 is being continuously rotated so as to continuously oscillate the mixing and cutting members within the barrel. The solid ingredients are thereby quickly mixed and the liquid ingredients are then introduced through the charge opening 12 in such manner as to be uniformly spread over the solid ingredients in the barrel. The continued operation of the mixing devices immediately and thoroughly distributes and mixes the liquid ingredients among the solid ingredients, and, when this mixing is completed, the moist mass begins immediately to be cut up by the action of the members 23. At this stage of the operation a small amount of lubricant, such as graphite, is introduced to coat the separate particles of explosives and to diminish any friction which might otherwise occur and to give the particles lustrous coating which is advantageous in the handling of the powder for commercial purposes. As soon as the granulation of the mixture has commenced, the barrel 9 is turned over to the position shown in Fig. 3 and the granulated particles are immediately thrown or pressed out through the meshes of the screen 11. Each particle is just sufficiently moist to have been easily cut and separated from the mass, while it is sufficiently solid to retain its own shape. A drying process, preferably with only the sun's heat, completes the powder for commercial use.

It will be seen that there is no chance whatever of creating metallic friction within the machine and consequently no opportunity for accidentally discharging the explosive. The members 23 do not quite touch the inner periphery of the barrel, the shaft 21 does not touch any portion of the barrel or trunnions, and the parts in general are so spaced apart that it is impossible for any

portion of the explosive to be caught between any moving parts. In addition to this, I construct all of the working parts where possible of a material which will not strike fire, wood being a preferred material throughout the device. The members 23 and the screen 11 are preferably made of copper wire. In order to hold the barrel in its two positions I may provide a retaining pin 35 which enters apertures 36 in one end of the barrel when the barrel is in either of its proper positions. The operation of the apparatus is thus reduced to utmost simplicity, it only being incumbent on the operator to admit certain proper quantities of the different materials in proper sequence and to turn the barrel when the granulation is effected. The machine thus becomes a complete powder plant with the mere exception of the bins for storage of materials and suitable trays or other means for drying the completed explosive. 80

Having described my invention, I claim:

1. A device of the character described comprising a barrel having a portion of its peripheral wall perforated and an opposite portion imperforated, hollow trunnions at the ends of the barrel, bearings for the trunnions to hold the barrel revolvably with its axis horizontal, a horizontal shaft passing through the trunnions and barrel, bearings for the shaft holding it clear of the trunnions, a radially extending mixing member on the shaft within the barrel, and means to oscillate the shaft. 85

2. A device of the character described comprising a barrel having a portion of its peripheral wall formed of wire screen and an opposite portion imperforated, hollow trunnions at the ends of the barrel, bearings for the trunnions to hold the barrel with its axis horizontal, a horizontal shaft passing through the trunnions and barrel, bearings for the shaft holding it clear of the trunnions, a radially extending member on the shaft within the barrel and comprising a frame secured to the shaft and spaced wire members extending therefrom to points close to the inner periphery of the barrel, and means to oscillate the shaft. 90

In witness that I claim the foregoing I have hereunto subscribed my name this 3d day of January 1912. 110
